BODY HEADREST FOR UNDERTAKERS' USE

Filed April 8, 1930

FIG. 1.

UNITED STATES PATENT OFFICE

JOSEPH H. SWEENEY, OF NASHVILLE, TENNESSEE

BODY HEADREST FOR UNDERTAKERS' USE

Application filed April 8, 1930. Serial No. 442,572.

This invention relates to a device for use by undertakers and embalmers while working upon a corpse.

The primary object of the present invention is to provide a device for maintaining the head of the corpse in a fixed position and for holding the lower jaw firmly against the upper jaw during the injection of the embalming fluid, the head being so held that the embalmer is enabled to message the entire face, neck and ears during the embalming operation.

Another object of the invention is to provide a device by means of which, after a cranial post-mortem examination, the removed portion of the skull may be held in replaced position while the plaster of Paris filler which is used in this operation is drying and hardening.

The invention will be best understood from a consideration of the following detailed description taken in connection with the accompanying drawings forming part of this specification, with the understanding, however, that the invention is not confined to any strict conformity with the showing of the drawings but may be changed or modified so long as such changes or modifications mark no material departure from the salient features of the invention as expressed in the appended claims.

In the drawings:

Figure 1 shows the device embodying the present invention in side elevation, showing in dotted position a head resting thereon.

Figure 2 is a view in top plan of the head support.

Figure 3 is a sectional view taken substantially on the line 3—3 of Figure 2.

Figure 4 is a sectional view taken on the line 4—4 of Figure 3.

Figure 5 is a sectional view through one of the feet of the stand showing the means for adjusting the height thereof.

Figure 6 is a sectional view taken on the line 6—6 of Figure 2.

Referring more particularly to the drawings wherein like numerals of reference indicate corresponding parts throughout the several views, the numeral 1 indicates gen-

erally the head rest base embodying the present invention, the same comprising a substantially rectangular frame 2 comprising the side bars 3 and the connecting bars 4. As shown each of the side bars 3 has formed therethrough a longitudinally extending series of apertures 5 and the transverse bars 4 which connect the side bars 3 are further connected by the concave substantially parallel head supporting bars 6 which lie parallel with the side bars 3.

At each corner of the frame 2 a foot post 7 is formed which threadably receives in its lower portion the shank of a screw 8 to which is attached a rubber button 9. As will be readily seen upon reference to Figure 1 longitudinal adjustment of the screws 8 will raise or lower the corners of the head support to which they are attached, as desired.

The frame 2 carries a head frame or yoke 10 which, as shown in Figure 2, is substantially U-shaped and has the terminal portions of the side arms 11 angularly directed as indicated at 12 and each is provided with a circumferential recess 13 for the purpose hereinafter described. The turned portion 12 of each side bar of the frame or yoke 10 is adapted to extend through an aperture 5 of a side bar 3 of the head rest frame and each side bar of this yoke is held in place by means of a sliding latch 14 carried by the adjacent bar 3 and surrounding it and having at one edge of the upper and lower portion thereof a notch 15 of the proper size to snugly receive that portion of the yoke bar about which the circumferential recess 13 is formed. It will thus be seen upon reference to Figure 3 of the drawing that the latch member 14 will securely hold the adjacent bar in place.

Pivotedly attached to each side bar 11 of the head yoke, intermediate its ends, is a brace bar 16 which is threaded throughout its length and carries a nut 17. The free end of each brace bar 16 is adapted to extend through an adjacent aperture 5, the nut 17 on the brace bar resting upon the top of the adjacent frame bar 3 in the manner shown in Figure 1. From this it will be readily seen that angular adjustment of the yoke 10 with regard to the frame 2 upon which the head

100

of the corpse rests may be readily made to bring the connecting portion 18 of the head yoke into the proper position for the engagement of a screw member carried thereby and about to be described, with the top of the head or with the chin of the body in the manner shown.

The head engaging screw carried by the cross bar 18 of the yoke 10 is indicated by the 10 numeral 19. This screw swivelly carries upon the end which is disposed within the yoke a button 20 while upon its other end a knob 21 is secured.

From the foregoing description it will be 15 readily seen that by using the device herein described the head of a body may be firmly held in the proper position for the introduction of embalming fluid into the body and for the necessary massaging of the face and 20 neck thereof during this operation. It will also be readily understood that by reversing the head support and lowering the yoke 10 the top of the skull may be firmly held in place by the screw 19 after the same has been 25 replaced following a post-mortem examination and while the plaster inserted for filling out the portions of the skull removed is hardening.

Having thus described my invention, what 30 I claim is:

1. A head rest of the character described, comprising a base, a frame disposed at an inclination from the horizontal, above and horizontally adjustable on the base, the frame being designed to have a head positioned 35 therein, means interposed between the frame and the base for vertically adjusting a transverse portion thereof, and means carried by the transverse portion for engaging a head 40 resting upon the base to hold the head in position thereon.

2. A head support of the character described, comprising a base consisting of a frame and members connecting opposite 45 sides thereof for supporting a head, a substantially U-shaped frame detachably connected at the ends of its side members with side members of the base frame, means for horizontally adjusting the U-shaped frame 50 on the base frame, means connecting the U-shaped frame with the base frame whereby the U-shaped frame may be vertically adjusted at one end and caused to assume an acute angle with and over the base frame, 55 and means carried by the U-shaped frame at the vertically adjustable end thereof for engaging a head resting upon the base.

3. A head support comprising a base portion 60 consisting of a frame having longitudinally apertured side members, concave members extending across the frame for the support of a head, legs supporting the frame, means for vertically adjusting each of said legs, and a head engaging unit carried by the 65 frame and adapted to be horizontally adjust-

able thereon by selective engagement with the apertures in the frame side members.

4. A body head support comprising a base 70 consisting of a frame having opposite side members thereof each provided with a longitudinally extending series of apertures, elements carried by the frame for supporting a head, a substantially U-shaped frame having the free end of each side portion thereof formed for engagement in one of said apertures, a shiftable latch carried by each of the apertured sides of the first mentioned frame for engaging and maintaining the side members of the second mentioned frame in position, means connecting the side members of the second mentioned frame with the side members of the base frame for vertically shifting the second mentioned frame, and a shiftable element carried by the second mentioned frame for engaging and holding in 85 position a head resting upon the base.

5. A head supporting structure comprising 90 a base having opposite side members each provided with a longitudinally extending series of apertures, a substantially U-shaped frame supported by said base and having the side members thereof each angularly disposed at its free end and provided with a circumferential recess for engagement in an aperture of a base side member, an arm pivotally attached to each side member of the U-shaped frame and adapted to extend through an aperture in the adjacent base side member, a nut threaded on each arm abutting the adjacent base and adapted to raise or lower 100 the arm and the attached frame, and a threaded member extended transversely through the yoke portion of the U-shaped frame for engagement with a head disposed in the frame and resting upon the base.

6. A head supporting structure comprising 105 a base having opposite side members each provided with a longitudinally extending series of apertures, a substantially U-shaped frame supported by said base and having the side members thereof each angularly disposed at its free end and provided with a circumferential recess for engagement in an aperture of a base side member, an arm pivotally attached to each side member of the U-shaped frame and adapted to extend through an aperture in the adjacent base side member, a nut threaded on each arm abutting the adjacent base and adapted to raise or lower 110 the arm and the attached frame, a threaded member extended transversely through the yoke portion of the U-shaped frame for engagement with a head disposed in the frame and resting upon the base, and a latch member shiftable on each side member of the 115 base for engaging the adjacent frame side portion to maintain the same in position.

7. A head rest of the character described, comprising a head supporting body, a substantially U-shaped frame having the end 120

of each side portion thereof connected with the body at one side of the same, said frame being disposed at an inclination from the horizontal, means connecting the side members of the frame with the body whereby the portion of the frame connecting the side members may be raised or lowered, and an element adjustably carried by the portion of the frame between the side members thereof

10 for engaging the chin of a head on the body.

8. A head rest of the character described, comprising a head supporting body, a substantially U-shaped frame having the free end of each side member thereof loosely connected with a side of the body, a screw member connected at one end with one side member of said frame and having its other end extending downwardly therefrom through an aperture in the body, a nut upon each screw

15 arranged to engage the body to lift the frame to an inclined position, and a member adjustably supported by the yoke portion of the frame and adapted to be shifted into engagement with the chin of a head positioned in the frame.

20 In testimony whereof I hereunto affix my signature.

JOSEPH H. SWEENEY.
